CLAIM

The ornamental design for a pool cleaner, as shown and described.

DESCRIPTION

FIG. 1 is an isometric view of a rear, top, and left side of an ornamental design for a pool cleaner;

FIG. 2 is a rear elevational view of the pool cleaner of FIG. 1;

FIG. 3 is a front elevational view of the pool cleaner of FIG. 1;

FIG. 4 is a left side elevational view of the pool cleaner of FIG. 1, the right side elevational view being a mirror image thereof;

FIG. 5 is a top plan view of the pool cleaner of FIG. 1; and, FIG. 6 is a bottom plan view of the pool cleaner of FIG. 1. The broken lines are for the purpose of illustrating environmental structure and form no part of the claimed design.
